UNITED STATES PATENT OFFICE.

ANDREW KOWALSKY, OF OAK PARK, ILLINOIS, ASSIGNOR TO INTERNATIONAL HARVESTER COMPANY, OF CHICAGO, ILLINOIS, A CORPORATION OF NEW JERSEY.

GREASE CUP.

Application filed June 19, 1922. Serial No. 569,275.

To all whom it may concern:

Be it known that I, ANDREW KOWALSKY, a citizen of the United States, residing at Oak Park, in the county of Cook and State 5 of Illinois, have invented certain new and useful Improvements in Grease Cups, of which the following is a full, clear, and exact specification.

This invention relates to grease cups of 10 the compression type consisting of a stationary base adapted to be screwed into the part to be greased and of a top part or cap which is internally threaded to engage over the externally threaded top of the base, and 15 the invention is more particularly directed to means for preventing the top from unscrewing or working loose as the result of vibration of the part on which the cup is carried. I attain the object desired by providing the cup with a locking device or 20 detent which, while permitting screwing and unscrewing of the cap upon the bottom part or base of the cup, will, at the same time, act automatically to hold and practically lock 25 the two parts in adjusted position so firmly as to overcome the effect of vibration, and my invention consists in an improved construction and arrangement of elements for the purpose stated, as will be understood 30 from the following description and by reference to the accompanying drawings in which—

Fig. 1 is a side view of a cup including my invention, with parts of the cap and base 35 broken away to show the interior construction;

Fig. 2 is a side view of the cup base;

Fig. 3 is a top view of the cup base with the detent spring in place;

Fig. 4 is a similar view without the spring;

Fig. 5 is a detail sectional view taken on the line 5—5 of Fig. 3, but with the cap in place, showing the relation of the detent 45 spring to the base and cap;

Fig. 6 is a similar view with cap omitted taken on the line 6—6 of Fig. 3; and

Fig. 7 is a detail view of the detent spring.

The cup consists of a base 10 provided 50 with an externally threaded shank 11 which is preferably formed with a wrench receiving surface 12. The base 10 has an externally threaded annular rim 13 and at one point the edge of this rim is cut out to form 55 a kerf or opening 14 the end walls of which

are undercut as at 14^a to provide the overhanging free corners 14^b. The cover or cap 15 which holds the grease is threaded internally to engage the externally threaded rim 13 on the base and, by rotating the cap by 60 hand, it may be moved upon the threaded rim 13 up or down according to the direction of rotation. To overcome the effect of vibration upon the cup which tends to unscrew or loosen the cover, I provide, between the 65 meeting faces of the cap and base of the cup, an automatically acting yielding detent or lock which, while yielding to permit screwing of the cap upon the base by hand, will, at the same time, operate to lock or hold the 70 parts in their adjusted position with sufficient firmness to prevent the cap from jarring loose by vibration. This detent consists of a resilient element such as the length 75 of spring wire 16 which is curved to conform to the shape of the cup and positioned within the edge of the cup base with a portion extending across the opening or kerf 14. The part of the spring wire extending across the opening 14 is kinked or bent out- 80 wardly as at 17 in a manner to protrude slightly beyond the side of the base so as to engage the threads on the cap 15. In order to retain the detent spring 16 in position within the base, the free corners 14^b on each 85 side of the kerf 14 are bent inwardly over the spring wire 16 as best seen in Fig. 3, and the edge of the rim 13 is indented at a plurality of equally spaced points in its circumference as at 18, the inturned corners 14^b 90 and dents 18 together constituting means for preventing dislodgement of the detent spring which is not otherwise secured at any point to the cup base.

With the construction above described, 95 there is provided a resilient protuberance on the base of the cup consisting of the bend 17 of the spring detent which bend presents a considerable portion of its outer face to the threads on the inside of the cap 15 making 100 a yielding pressure thereon and causing a degree of frictional resistance sufficient to entirely overcome the loosening or unscrewing effect of jarring or vibration of the part on which the cup may be used.

While the specific form of my invention above described is that preferred, variations therefrom are contemplated within the scope of the following claim:

In a grease cup, the combination of a base 110

having an undercut kerf in its edge, a cap threaded on the base, and a length of resilient wire positioned within the edge of the base and extending across said kerf and formed with a bend protruding there-through and engaging the threads on the cap, the free corners of the kerf being bent

inwardly over the wire and the edges of the base being formed with inward indentations at spaced points to retain the wire in position. 10

In testimony whereof I affix my signature.

ANDREW KOWALSKY.
